(57) **CLAIM**

The ornamental design for a pair of display screens with animated graphical user interface, as shown and described.

DESCRIPTION

FIG. 1 is a front view of a first embodiment of a pair of display screens with animated graphical user interface showing a first image in a sequence, showing our new design; FIG. 2 is a front view showing a second image thereof; FIG. 3 is a front view showing a third image thereof; FIG. 4 is a front view showing a fourth image thereof; FIG. 5 is a front view showing a fifth image thereof; FIG. 6 is a front view showing a sixth image thereof; FIG. 7 is an enlarged view of the portion defined by lines 7-7 in FIG. 1; FIG. 8 is an enlarged view of the portion defined by lines 8-8 in FIG. 2; FIG. 9 is an enlarged view of the portion defined by lines 9-9 in FIG. 3; FIG. 10 is an enlarged view of the portion defined by lines 10-10 in FIG. 4; FIG. 11 is an enlarged view of the portion defined by lines 11-11 in FIG. 5; FIG. 12 is an enlarged view of the portion defined by lines 12-12 in FIG. 6; FIG. 13 is a front view of a second embodiment of a pair of display screens with animated graphical user interface showing a first image in a sequence, showing our new design; FIG. 14 is a front view showing a second image thereof;

(Continued)

FIG. 15 is a front view showing a third image thereof; FIG. 16 is a front view showing a fourth image thereof; FIG. 17 is a front view showing a fifth image thereof; FIG. 18 is a front view showing a sixth image thereof; FIG. 19 is an enlarged view of the portion defined by lines 19-19 in FIG. 13; FIG. 20 is an enlarged view of the portion defined by lines 20-20 in FIG. 14; FIG. 21 is an enlarged view of the portion defined by lines 21-21 in FIG. 15; FIG. 22 is an enlarged view of the portion defined by lines 22-22 in FIG. 16; FIG. 23 is an enlarged view of the portion defined by lines 23-23 in FIG. 17; FIG. 24 is an enlarged view of the portion defined by lines 24-24 in FIG. 18; FIG. 25 is a front view of a third embodiment of a pair of display screens with animated graphical user interface showing a first image in a sequence, showing our new design; FIG. 26 is a front view showing a second image thereof; FIG. 27 is a front view showing a third image thereof; FIG. 28 is a front view showing a fourth image thereof; FIG. 29 is a front view showing a fifth image thereof; FIG. 30 is a front view showing a sixth image thereof; FIG. 31 is an enlarged view of the portion defined by lines 31-31 in FIG. 25; FIG. 32 is an enlarged view of the portion defined by lines 32-32 in FIG. 26; FIG. 33 is an enlarged view of the portion defined by lines 33-33 in FIG. 27; FIG. 34 is an enlarged view of the portion defined by lines 34-34 in FIG. 28; FIG. 35 is an enlarged view of the portion defined by lines 35-35 in FIG. 29; FIG. 36 is an enlarged view of the portion defined by lines 36-36 in FIG. 30; FIG. 37 is a front view of a fourth embodiment of a pair of display screens with animated graphical user interface showing a first image in a sequence, showing our new design; FIG. 38 is a front view showing a second image thereof; FIG. 39 is a front view showing a third image thereof; FIG. 40 is a front view showing a fourth image thereof; FIG. 41 is a front view showing a fifth image thereof; FIG. 42 is a front view showing a sixth image thereof; FIG. 43 is an enlarged view of the portion defined by lines 43-43 in FIG. 37; FIG. 44 is an enlarged view of the portion defined by lines 44-44 in FIG. 38; FIG. 45 is an enlarged view of the portion defined by lines 45-45 in FIG. 39; FIG. 46 is an enlarged view of the portion defined by lines 46-46 in FIG. 40; FIG. 47 is an enlarged view of the portion defined by lines 47-47 in FIG. 41; FIG. 48 is an enlarged view of the portion defined by lines 48-48 in FIG. 42; FIG. 49 is a front view of a fifth embodiment of a pair of display screens with animated graphical user interface showing a first image in a sequence, showing our new design; FIG. 50 is a front view showing a second image thereof; FIG. 51 is a front view showing a third image thereof; FIG. 52 is a front view showing a fourth image thereof; FIG. 53 is a front view showing a fifth image thereof; FIG. 54 is a front view showing a sixth image thereof;

FIG. 55 is an enlarged view of the portion defined by lines 55-55 in FIG. 49; FIG. 56 is an enlarged view of the portion defined by lines 56-56 in FIG. 50; FIG. 57 is an enlarged view of the portion defined by lines 57-57 in FIG. 51; FIG. 58 is an enlarged view of the portion defined by lines 58-58 in FIG. 52; FIG. 59 is an enlarged view of the portion defined by lines 59-59 in FIG. 53; FIG. 60 is an enlarged view of the portion defined by lines 60-60 in FIG. 54; FIG. 61 is a front view of a sixth embodiment of a pair of display screens with animated graphical user interface showing a first image in a sequence, showing our new design; FIG. 62 is a front view showing a second image thereof; FIG. 63 is a front view showing a third image thereof; FIG. 64 is a front view showing a fourth image thereof; FIG. 65 is a front view showing a fifth image thereof; FIG. 66 is a front view showing a sixth image thereof; FIG. 67 is an enlarged view of the portion defined by lines 67-67 in FIG. 61; FIG. 68 is an enlarged view of the portion defined by lines 68-68 in FIG. 62; FIG. 69 is an enlarged view of the portion defined by lines 69-69 in FIG. 63; FIG. 70 is an enlarged view of the portion defined by lines 70-70 in FIG. 64; FIG. 71 is an enlarged view of the portion defined by lines 71-71 in FIG. 65; FIG. 72 is an enlarged view of the portion defined by lines 72-72 in FIG. 66; FIG. 73 is a front view of a seventh embodiment of a pair of display screens with animated graphical user interface showing a first image in a sequence, showing our new design; FIG. 74 is a front view showing a second image thereof; FIG. 75 is a front view showing a third image thereof; FIG. 76 is a front view showing a fourth image thereof; FIG. 77 is a front view showing a fifth image thereof; FIG. 78 is a front view showing a sixth image thereof; FIG. 79 is an enlarged view of the portion defined by lines 79-79 in FIG. 73; FIG. 80 is an enlarged view of the portion defined by lines 80-80 in FIG. 74; FIG. 81 is an enlarged view of the portion defined by lines 81-81 in FIG. 75; FIG. 82 is an enlarged view of the portion defined by lines 82-82 in FIG. 76; FIG. 83 is an enlarged view of the portion defined by lines 83-83 in FIG. 77; and, FIG. 84 is an enlarged view of the portion defined by lines 84-84 in FIG. 78. The outermost broken lines in the figures depict display screens and form no part of the claimed design. The remainder of the broken lines depict portions of the graphical user interface that form no part of the claimed design. The dot-dot-dash broken lines in the figures identify partially enlarged views and are for reference only and form no part of the claimed design. The appearance of the transitional image sequentially transitions between the images shown in FIGS. 1-6, FIGS. 13-18, FIGS. 25-30, FIGS. 37-42, FIGS. 49-54, FIGS.

61-66, and FIGS. 73-78, respectively. The process or period in which one image transitions to another image forms no part of the claimed design.
